UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No: 30,810, dated May 16, 1899.

Application filed April 22, 1899. Serial No. 714,117. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming part thereof, in which—

Figure 1 is a top or plan view of a manhole-cover, illustrating my design; and Fig. 2 is a cross-sectional view thereof.

The two views are deemed necessary for a proper illustration and understanding of the design of my invention.

As illustrated in the drawings, the leading feature of my design consists in the configuration or outline of the manhole-cover as well as the surface ornamentation thereof. When viewed in plan, the upper surface of the cover presents the appearance of a central field *a*, lying within a circular border *b*, the

inner rim or edge of which border being formed of a series of long sectors *d*, joined together by oppositely-arranged short sectors *d'*. When viewed in cross-section, the cover is cup-shaped and has an inwardly-bulged or convex-shaped base *e*, from which projects upward the rim *e'*, forming on its upper flat surface the border *b* of the cover. From the lower face of the base *e* project the two rib-like ornaments *f* and *g*, arranged at right angles to each other.

Having thus described my invention, what I claim as new, and desire to secure by Letters Patent, is—

The design for a manhole-cover, substantially as illustrated and herein described.

In testimony whereof I have hereunto set my signature in the presence of two subscribing witnesses.

THOMAS P. GREGER.
